US00D554139S

(12) **United States Design Patent** (10) Patent No.: **US D554,139 S**
(45) Date of Patent: **** Oct. 30, 2007**

(54) **TIME DISPLAY ON ELECTRONIC DEVICE SCREEN**

(75) Inventor: **Ae-Jung Seo**, Seoul (KR)

(73) Assignee: **Samsung Electronics Co., Ltd.** (KR)

(**) Term: **14 Years**

(21) Appl. No.: **29/232,075**

(22) Filed: **Jun. 14, 2005**

(30) **Foreign Application Priority Data**

Dec. 16, 2004 (KR) 30-2004-0038730

(51) **LOC (8) Cl.** **14-04**

(52) **U.S. Cl.** **D14/486**

(58) **Field of Classification Search** D14/129, D14/485-496; D10/15; D18/24-33; D19/6; D20/11; D21/324-33; 715/700, 703, 706, 715/716, 727, 763, 764, 775, 779, 810, 834, 715/835, 837-40, 846-7, 864, 900, 715, 715/719, 748, 761-2, 769, 771, 776, 809, 715/812-3, 836, 977

See application file for complete search history.

(57) **CLAIM**

I claim, the ornamental design for a time display on electronic device screen, as shown and described.

DESCRIPTION

The FIGURE is a front elevational view of a time display on electronic device screen, showing our new design.

The broken line in the FIGURE is to illustrate a device screen and forms no part of the claimed design.

1 Claim, 1 Drawing Sheet
